CLAIM

The ornamental design for a multiple function image switching attachment for a telescope or similar article, substantially as shown and described.

DESCRIPTION

FIG. 1 is a top plan view of a multiple function image switching attachment for a telescope or similar article showing my new design;

FIG. 2 is a front elevational view thereof;

FIG. 3 is a bottom plan view thereof;

FIG. 4 is a rear elevational view thereof;

FIG. 5 is a side elevational view thereof; and

FIG. 6 is a cross-sectional view thereof, taken along line 6—6 of FIG. 2.

FIG. 1

FIG. 3

FIG. 2

FIG. 4

FIG. 5

FIG. 6

UNITED STATES PATENT AND TRADEMARK OFFICE
CERTIFICATE OF CORRECTION

PATENT NO. : D310,381

DATED : Sep. 4, 1990

INVENTOR(S) : Jeffrey R. Charles

It is certified that error appears in the above-identified patent and that said Letters Patent is hereby corrected as shown below:

On the title page;
Column 2, last line under OTHER PUBLICATIONS, "micron" should read
"mirror".

Column 2, description from Fig. 5 onwards under DESCRIPTION, should
read:

FIG. 5 is a right side elevational view thereof;
FIG. 6 is a cross-sectional view thereof, taken along line
6-6 on FIG. 2;
FIG. 7 is a perspective view thereof; and
FIG. 8 is a left side elevational view thereof.

Signed and Sealed this
Twenty-second Day of September, 1992

Attest:

DOUGLAS B. COMER

Attesting Officer

Acting Commissioner of Patents and Trademarks
